UNITED STATES PATENT OFFICE.

JOEL HEACOCK, OF MARLBOROUGH, OHIO.

IMPROVEMENT IN FIELD-FENCES.

Specification forming part of Letters Patent No. **65,670**, dated June 11, 1867.

To all whom it may concern:

Be it known that I, JOEL HEACOCK, of Marlborough, county of Stark, in the State of Ohio, have invented a new and Improved Mode of Constructing Field-Fence; and I do hereby declare that the following is a full and exact description thereof, reference being had to the accompanying drawings, and to the letters of reference marked thereon.

Figure 1 is a front or outside view. Fig. 2 is a rear or inside view.

The nature of this improvement consists in constructing a panel-fence out of the common split rails used in laying up the ordinary worm-fence, in such a manner that it is self-sustaining and portable, does not occupy as much room, and is much more economical than the worm-fence, as sixteen rails only are required to make as much fence as forty rails will in the ordinary manner, and any panel may be readily removed in case an entrance is desired through any portion of the fence.

To enable others to fully understand my improvement, I will describe its construction.

I take the desired number of rails A A, lay them down side by side, leaving the proper space or distance between them; then join them by boards or strips B B, which are attached to each rail by nailing the strip on one end of the panel, and if the rail is crooked or twisted the corners are to be hewn off, and made to fit the other strip. When the panel is thus formed I lay down the sill D in its place where the fence is to stand, set up the panel with the end on the sill, near the middle, and attach it by nailing through the cor-

ner of the rail; then join the next panel by setting it on the same sill, as shown in the drawing. The brace C is then put on by allowing its lower edge to rest on the third rail, with its upper end E fitting in a notch, e, in the top rail previously made to receive it, its lower end being adjusted before nailing, so as to bring the panels together firmly, thus answering the double purpose of holding the panels together, as well as in their upright position. To form the corner of the fence, the brace C' and sill D' are secured along the side of the panel, instead of across. There are no posts used, and each panel is independent of the other, and may be easily removed for entrance or repairs.

A field or farm fence constructed as above described, and of the material specified, possesses several advantages over others in this respect: economy of labor and material, and is very easily constructed, and is easily removed, being portable.

Having thus described my improvement, what I claim as new, and desire to secure by Letters Patent, is—

The combination and arrangement, herein described, of the rails A A, battens B B, braces C, and sill D, when all are constructed of the ordinary split rails, to form the panels of a field-fence, substantially in the manner and for the purpose set forth and described.

JOEL HEACOCK.
